G. W. HALL ET AL

JOURNAL LUBRICATOR

Filed Feb. 14, 1921

FIG. 1.

FIG. 2.

G.W.HALL AND M.P.COCHRANE

By W. J. Fitz Gerald & Co.

Attorney

Inventor

UNITED STATES PATENT OFFICE.

GEORGE W. HALL AND MARK P. COCHRANE, OF BRAINERD, MINNESOTA.

JOURNAL LUBRICATOR.

Application filed February 14, 1921. Serial No. 444,885.

To all whom it may concern:

Be it known that we, GEORGE W. HALL and MARK P. COCHRANE, citizens of the United States, residing at Brainerd, in the county of Crow Wing and State of Minnesota, have invented certain new and useful Improvements in Journal Lubricators; and we do hereby declare the following to be a full, clear, and exact description of the invention, such as will enable others skilled in the art to which it appertains to make and use the same.

The present invention relates generally to lubricators and more particularly to such devices for oiling or lubricating the journals of railroad cars, it being the object of the invention to provide a novel and improved lubricator for application to a journal within the journal box, for lubricating the journal in a thoroughly efficient and reliable manner.

It is also the object of the invention to provide such a lubricator which is simple and inexpensive in construction, and which can be readily placed within and removed from an ordinary journal box without requiring alterations therein.

A further object is the provision of a journal lubricator provided with novel means to accommodate and fit the journal and retain the lubricator in operative position.

A still further object is the provision of novel means to fit the journal and supply the lubricant thereto, whereby the surface of the journal is kept lubricated.

With the foregoing and other objects in view, which will be apparent as the description proceeds, the invention resides in the construction and arrangement of the component parts, it being understood that changes can be made within the scope of what is claimed without departing from the spirit of the invention.

The invention is illustrated in the accompanying drawings, wherein:—

Figure 1 is a medium longitudinal vertical section of the journal box and lubricator therein, showing the journal and other parts in elevation.

Fig. 2 is an enlarged cross section of the lubricator on the line 2—2 of Fig. 3.

Fig. 3 is a plan view thereof, portions being broken away.

In Fig. 1 there is illustrated an ordinary journal box 1 located at the outer side of the respective car wheel 2 from which the journal 3 of the axle projects within the journal box as usual, the journal has a collar 4 at the end, and the bearing 5 seats on the journal 3 in accordance with standard practice. The journal box 1 has a cover or closure 1^a to permit access to be had to the journal as usual.

The present lubricator comprises a reservoir or cellar 6 for the oil or other lubricant, and the top of the reservoir or chamber has a longitudinal concaved channel or recess 7 concentric with the lower portion of the journal 3, so that the reservoir lies below the bottom of the journal. The ends of the channel 7 are open and at the outer end of the channel 7 the top of the reservoir has a transverse groove or cut-away portion 8 for the purpose of receiving the collar 4, as seen in Fig. 1. This serves to maintain the lubricator in longitudinal position, as well as accommodating said collar. The outer end of the reservoir extends upwardly, as at 9, across the outer end of the channel or depressed portion of the top, and this extension rises above the bottom of the channel and is widened, as seen in Fig. 3, to hold lubricant in reserve. Thus, the lubricant within said chamber can be maintained at a level above the bottom of the channel, the extension or portion 9 being provided with an upper filling opening 10 closed by a removable plug or cap 11, so that when the cover 1^a of the journal box is swung open it is an easy matter to remove the plug 11, on account of its being located beyond the outer end of the journal adjacent to the opening of the journal box, when the cover is opened. This renders it convenient for filling the reservoir from time to time.

In order to provide for the feeding of the lubricant to the journal, the bottom of the channel or depression 7 of the top of the reservoir, is provided with a central longitudinal slot 12, and a pad 13 of leather, felt or other absorbent porous material is disposed over the channel 7 and is arcuate in section to fit the bottom and sides of the

journal. The reservoir is provided with flanges or lips 14 extending along the edges of the channel 7, and the pad 13 extends across said flanges 14. A secondary pad 15 is secured to the lower surface of the main pad 13, by means of rivets or clinched nails 16, and fits snugly in and on the channel 7 with its edges abutting the flanges 14, and a strip 17 is secured similarly to the lower surface of the pad 15 and fits snugly down in the slot 12. To keep the edge portions of the pad 13 snugly against the sides of the journal, arcuate leaf springs 18 extend transversely under the pad 13 and over the pad 15 at suitably spaced longitudinal points, and said springs are clamped and secured between the pads, and the end portions of the springs are secured to the pad 13 by means of rivets 19 or the like. These springs 18 tend to curl up slightly, whereby their end portions bend toward the journal, thereby holding the edge portions of the pad 13 snugly against the journal, while the central longitudinal portion of the pad is held snugly up against the lower surface of the journal. The strip 17 fitting in the slot 12 will hold the pads in place and the pad 15 and strip 17 are preferably of the same material as the pad 13.

30 Apertures 20 are provided in the central longitudinal portion of the pads 13 and 15 and strip 17 at suitably spaced points to open into the reservoir, whereby the lubricant can flow upwardly through the apertures in which eyelets 21 are preferably fitted from above so that the lubricant flows upwardly to the journal, and the lubricant will be absorbed by the pad 13, to distribute the lubricant throughout the area of the 40 pad and contacting surface of the journal. This will spread the lubricant in a film over the journal, thereby keeping the contacting surfaces of the journal and bearing well lubricated. It is noted that the journal 3 covers or closes the eyelets 21 to prevent too rapid flow of lubricant, and the lubricant works gradually from said eyelets between the pad and journal as needed.

As a means for retaining the lubricator 50 up against the journal, coiled wire expansion or lifting springs 22 are disposed underneath the reservoir at suitable points thereof, and their upper ends abut the bottom of the reservoir and are preferably secured around bosses 23 depending from the bottom of the reservoir. Thus, when the lubricator is inserted into the journal box and pushed under the journal, the springs 22 will be compressed, and when the lubricator is moved home the springs will lift it up against the journal with desired tension, the springs 22 seating on the bottom of the journal box.

The reservoir 6 can be readily cast from 65 suitable metal in one piece or can be other-

wise manufactured at small cost, and the lubricator can be made and installed with minimum expense, labor and time, but nevertheless it will serve its office in a highly satisfactory manner. 70

Having thus described the invention, what is claimed as new is:

1. A lubricator comprising a lubricant reservoir having a top provided with means for the upward flow of lubricant therethrough, an absorbent pad to fit against a journal, the secondary pad attached to the first named pad to fit on the top of said reservoir, the first named pad having its edge portions projecting beyond the secondary pad, and spring means for pressing the projecting edge portions of the first named pad against the journal. 75

2. A lubricator comprising a lubricant reservoir having a channel, an arcuate pad extending across the channel to fit against a journal, and a secondary arcuate pad attached to the aforesaid pad and fitted in said channel, said channel having means for the flow of lubricant to the pads, the first named pad being wider than the secondary pad with its edge portions projecting beyond the edges of the secondary pad and reservoir. 80

3. A lubricator comprising a lubricant reservoir having a top provided with a slot, a pad disposed over said top to fit a journal, and a strip attached to the pad and fitted in said slot, said pad and strip having apertures for the flow of lubricant therethrough from the reservoir to the journal. 90

4. A lubricator comprising a lubricant reservoir having a top provided with a channel having means for the flow of lubricant therethrough, and an absorbent pad extending across said channel and curved to fit against a journal, a secondary pad attached to the aforesaid pad and fitted in said channel, and transverse arcuate spring means between the pads for pressing the first 100 named pad against the journal. 105

5. A lubricator comprising a lubricant reservoir having a top provided with a channel having a longitudinal slot, a pad extending across the channel to fit a journal, 115 a secondary pad attached to the aforesaid pad and fitted snugly in said channel, a strip attached to the secondary pad and fitted in said slot, said pads and strip having apertures for the flow of lubricant therethrough. 120

6. A lubricator comprising a lubricant reservoir having a slot or opening, a pad seated against the reservoir and having a portion fitted in said slot or opening, said 125 pad and portion being apertured for the outward flow of lubricant from the reservoir to the journal.

7. A lubricator comprising a lubricant reservoir having a top with means for the 130

upward flow of lubricant therethrough, an absorbent pad fitted on said top of the reservoir and having edge portions projecting beyond the reservoir and upwardly to fit the sides of a journal, and spring means for pressing said edge portions of the pad against the journal.

In testimony whereof we have signed our

GEORGE W. HALL.
MARK P. COCHRANE.
